UNITED STATES PATENT OFFICE.

WILLIAM E. SOMERVILLE, OF COAL CITY, ILLINOIS.

TOILET.

1,130,441.

Specification of Letters Patent.

Patented Mar. 2, 1915.

Application filed May 4, 1914. Serial No. 886,192.

To all whom it may concern:

Be it known that I, WILLIAM E. SOMERVILLE, a citizen of the United States, residing at Coal City, in the county of Grundy and State of Illinois, have invented new and useful Improvements in Toilets, of which the following is a full, clear, concise, and exact description, reference being had to the accompanying drawing, forming a part of this specification.

My invention relates to improvements in toilets with especial reference to those adapted for use in railroad cars and boats and has for its object the production of a device embodying two receptacles each arranged to open and close independently of the other.

A further object is the production of a device that can be easily made and assembled and one that is not liable to disarrangement of parts.

These and such other objects as may herein-after appear are attained by my device, an embodiment of which is illustrated in the accompanying drawings, in which—

Figure 1 represents a side elevation of my device; Fig. 2 represents a sectional view through the center line showing the device proper.

Like numerals of reference indicate like parts in the several figures of the drawings.

Referring now to the drawings, 1 represents a car floor, 2 a partition, 3 the toilet, comprising in the main the upper toilet or receptacle 4, a lower chamber or receptacle 5 and a passage 5^a connecting the chambers.

The upper chamber is provided with a movable bottom 6 operable from within in any desired manner, as by means of the handle 7 and lever connection 8, 8. It is to be noted that the washer 9 is interposed between the movable bottom 6 and the wall 10 of the upper receptacle, the idea being to make a water-tight joint between the receptacles. The lower receptacle 5 is also

provided with a movable bottom 11, which can be swung open by means of levers 12 and 13 and a handle 14. It will be noted that this handle 14 is preferably placed opposite to the compartment in which the toilet is located and means, such as a link 15, are provided at the top of this handle member which can be swung into engagement with a hook 16, leaving the bottom 11 permanently open if desired. A cover 17 is provided hinged at 18, in any desired manner.

It often becomes advisable when trains

are stopping in a station or passing through to close the lower receptacle, which can be done by the porter without in any way affecting the use of the device; at the same time, the ability to do this is entirely out of the control of the passengers and rests only with the porter or party in charge.

The device is of very simple construction, and, as shown is made preferably of a single porcelain or metallic member so as to be easily kept clean and not liable to breakage when put in place.

It is of course understood that any suitable flushing means are employed but not shown, the water remaining in the upper receptacle and aiding in the sealing of the receptacle.

Having thus described my invention, what I claim as new and desire to secure by Letters Patent is:

1. A device of the class described, comprising a pair of communicating receptacles arranged one over the other and each having a discharge opening, a closure for each opening to retain the contents in each receptacle and forming a sealed compartment of the lower receptacle between the closures, and a manually controlled operating means for each closure, said operating means being separate and distinct from and operable wholly independent of each other.

2. A device of the class described, comprising a pair of communicating receptacles arranged one over the other and each having a discharge opening, a closure for each opening to retain the contents in each receptacle and forming a sealed compartment of the lower receptacle between the closures, a manually controlled operating means for each closure, each of said operating means being separate and distinct from and operable wholly independent of each other, and means for securing the lower closure in an open position.

3. A device of the class described, comprising a pair of communicating receptacles arranged one over the other and each having a discharge opening, a closure for each opening to retain the contents in each receptacle and forming a sealed compartment of the lower receptacle between the closures, a manually controlled operating means for each closure, each of said operating means being separate and distinct from and operable wholly independent of each other, the operating means of the lower closure being

inaccessible to a person using the other closure operating means, and means for securing the lower closure in an open position.

4. A toilet, comprising a pair of communicating receptacles arranged one above the other, a sealing closure for each of said receptacles adapted to form a sealed chamber between the closures, and a separate operating means for each of said closures, said 10 operating means being positioned distant from each other to prevent the user of one from using the other and whereby the lower

closure can be closed to form said sealed chamber between the closures and leaving the upper closure free to be operated without opening the lower closure.

In witness whereof, I have hereunto subscribed my name in the presence of two witnesses.

WILLIAM E. SOMERVILLE.
